(57) **ABSTRACT**

New systems, devices and methods for extremely precise aiming and shooting of firearms are provided. In some embodiments, predicted projectile impacts may be selected and adjusted, prior to execution. In some embodiments, a device including specialized computer hardware and software aids a user in planning a shot(s), evaluating the accuracy of the planned shot(s), adjusting the location of the planned shot(s), and executing the planned shots. In some embodiments, smart bullets with on-board electronics, active aerodynamics, and wireless communications capabilities adjust a flight path of the smart bullet in-flight, to match a selected target location and/or flight path. In some embodiments, an active firearm barrel may counteract and/or otherwise adjust for any other relevant ballistic and other accuracy-impacting factors with a position-actuable firing mechanism to maintain a projected flight path of such a point of impact.

CROSS-REFERENCE TO RELATED APPLICATIONS

This application is a continuation-in-part of U.S. patent application Ser. No. 17/088,575, filed Nov. 3, 2020, now U.S. Pat. No. 11,268,789, which is a continuation-in-part of U.S. patent application Ser. No. 16/280,017, filed Feb. 19, 2019, now U.S. Pat. No. 10,823,533, which is a continuation-in-part of U.S. patent application Ser. No. 15/628,614, filed Jun. 20, 2017, now U.S. Pat. No. 10,209,035, which is a continuation-in-part of U.S. patent application Ser. No. 13/615,513, filed Sep. 13, 2012, now U.S. Pat. No. 9,683,813. This application is also a continuation-in-part of U.S. patent application Ser. No. 15/245,165, filed Aug. 23, 2016, now U.S. Pat. No. 9,778,003, which is a continuation-in-part of U.S. patent application Ser. No. 14/828,514, filed Aug. 17, 2015, now U.S. Pat. No. 9,423,223, which is a continuation-in-part of U.S. patent application Ser. No. 13/666,965, filed Nov. 2, 2012, now U.S. Pat. No. 9,109,864. The entire contents of each of the above applications are hereby incorporated by reference into the present application as if fully set forth herein.

FIELD OF THE INVENTION

The present invention relates to the field of firearms, and targeting systems and methods.

BACKGROUND

Projectile-firing weapons have been in use at least since the end of the upper Paleolithic period, when archery (the “bow and arrow”) had been invented. A bow is a projectile-firing weapon in which at least one flexible member creates tension in an attached line, which line may be drawn, flexing the member, and then released to propel a projectile known as an arrow by the elastic rebound of the member and line. In modern warfare, firearms and ballistic missiles use propellants to accelerate projectiles at much higher speeds and to strike distant targets, some of which may be difficult, or even impossible, to view with the naked eye. To capitalize on those capabilities and help direct such projectiles to their distant targets, targeting science has been developed.

A wide variety of aiming devices, known as “sights,” have been developed, and allow a user to aim a projectile weapon at a target using the user’s vision to align the two. For example, a rifle-mounted telescopic sight (a.k.a. “scope”) allows a marksman to target distant subjects, typically including the use of optic lenses and a superimposed reticle, often in the form of crosshairs meeting at a point associated with a point of impact of the projectile (a.k.a. “point of impact,” “Impact Point,”) at a target within an environment. Such a point of impact may be referred to as a “possible point of impact,” meaning that, if, and only if, the firearm is fired while the point of impact is indicated at that point, will the projectile then fired impact at that point in the environment. Using scopes mounted on high-powered, long-range rifles, highly skilled military and police marksmen, known as snipers, may successfully target and hit subjects at an effective range above 1,000 meters.

However, environmental and user factors can greatly impact the accuracy of rifle and other projectile weapon fire, especially in the instance of ballistic projectiles from hand-held weapons, and especially when fired by less skilled

shooters. These factors include, but are not limited to: 1) air density, 2) wind, 3) humidity, 4) visibility, 5) air quality, 6) elevation from subject, 7) ambient temperature, 8) hand and body tremor of the user, 9) shake and misalignment due to trigger pull, 10) flinching due to shot anticipation or environmental activity, 11) movement due to breathing, 12) movement due to heartbeat, 13) errant movements, 14) eye shift not addressed by the sight (parallax effect), 15) environmental structural changes or nudges (e.g., sand bag or tripod sinking, nudge from fellow person or other animal), 16) changes or states of change of any of the above factors, and 17) target object or other more general environmental movement. At longer firing ranges, the impact of these environmental and user factors, and resulting targeting inaccuracy, can be exponentially amplified. But greater ranges are beneficial, because they allow a sniper to maintain a safe distance from enemy forces and remain undetected. If snipers are located, critical missions may fail, and, in military campaigns, shooters, such as snipers, may be captured and assassinated.

Advanced reflecting and collimating sights, such as “red dot” sights, are designed to provide rapid acquisition and targeting with both eyes open and observing the entire environment as well as sight components. Such sights may also reduce or substantially eliminate the parallax effect that occurs when the shooter shifts eye position relative to the reticle of a scope or iron sights.

It should be understood that the disclosures in this application related to the background of the invention, in, but not limited to this section titled “Background,” do not necessarily set forth prior art or other known aspects exclusively, and may instead include art that was invented concurrently or after the present invention and conception, and details of the inventor’s own discoveries and work and work results.

SUMMARY OF THE INVENTION

New targeting systems, hardware and techniques are provided. These systems enable a user to plan shooting or other measures with extreme precision within an environment, evaluate the plan’s effectiveness, and execute the plan rapidly. In some aspects of the invention, a user of a targeting system according to some embodiments of the present invention may create, set, adjust and execute projected point(s) of impact, as shown by indicator(s), of a projectile on a target within a target environment (e.g., in a specialized augmented reality sighting display). In other aspects, the system may counteract and/or avoid certain ballistic, viewing perspective and projectile accuracy-affecting factors, in both a sighting display and in a projectile firing mechanism. Yet, in some embodiments, the systems, hardware and techniques so counteract or avoid those factors while maintaining the influence of other factors, such as targeting movements by a user. In some embodiments, the systems, hardware and techniques allow for rapid targeting adjustment, by adjusting three-dimensional (“3D”) positions and rotational attitudes in real time, to maintain an environmental view and a point of impact, and indicator thereof, despite those factors. The system is unobtrusive, allowing the user to engage ordinary targeting activity.

In some embodiments, an auxiliary probe is first launched and deployed at, on and/or about a target. Extremely precise, deliberate targeting for future projectiles, weapons or non-lethal measures is then performed relative to the position and orientation of the probe, in some such embodiments.

In some embodiments, a system according to some aspects of the invention enables a user to, in effect, take a

projected, trial shot at a target subject within an environment, evaluate its results, and execute an actual shot matching the trial shot only if satisfied. More specifically, in some such embodiments, a user may aim a rifle at a target with a telescopic sight including a specialized display and issue a trial shot firing command. The specialized display may then overlay an indicator of projected point of impact (a.k.a., a point of impact indicator), evaluate the indicator and projected point of impact (and/or, in some such embodiments, other projected results), and then send a projectile to the point of impact only upon a user's subsequent command(s) (if satisfied with the projected point of impact indicator). If unsatisfied, in some embodiments, a user may adjust the location of such a point of impact indicator for specialized position adjustment tools of the system, rather than cancel, restart and set another point of impact indicator. Prior to aspects of the present invention, shots needed to either succeed or fail, with one, actual execution of the shot—often with disastrous, irreversible consequences.

In some aspects of the invention, the system may execute multiple points of impact together or in rapid succession. In some such embodiments, such points of impact may surround, lead, cover or otherwise have a diverse distribution on, about or at a target and/or projected path of a target subject, based on movement and other environmental factors, such as those discussed elsewhere in this application.

Aspects of the present invention may be applied to a wide variety of other technological fields, in addition to and/or as an alternative to firearms, military and police and/or security technologies, including, but not limited to, shipment and inventory tracking and photography fields.

In still other embodiments of the invention, a new form of projectile, which implements lift that increases at lower speeds to counteract gravitational drop, while maintaining rifle-driven spiraling, is provided.

Rules of Construction and General Notes:

It should be understood that, for convenience and readability, this application may set forth particular pronouns and other linguistic qualifiers of various specific gender and number, but, where this occurs, all other logically possible gender and number alternatives should also be read in as both conjunctive and alternative statements, as if equally, separately set forth therein.

Where any term is set forth in a sentence, clause or statement ("statement") in this application, each possible meaning, significance and/or sense of any term used in this application should be read as if separately, conjunctively and/or alternatively set forth in additional statement(s), after the sentence, clause or statement, as necessary to exhaust the possible meanings of each such term and each such statement.

The embodiments set forth in detail in this application are to ease the reader's understanding of inventions set forth herein and, as such, are only examples of the virtually innumerable number of alternative embodiments falling within the scope of the application. No specific embodiment set forth in this application should be read as limiting the scope of any claimed inventions. Where applicable, other devices and methods of carrying out particular tasks and mechanics of the invention will be apparent to those of ordinary skill in the art, and such other devices and methods may also, or alternatively, be used, in some embodiments of the invention, and should be considered incorporated into the specification and within the scope of the invention.

The Summary, the Abstract, and other parts of the application, are for ease of understanding only, and no part of this

application should be read to limit the scope of the invention, whether or not it references matter also set forth in any other part.

5 BRIEF DESCRIPTION OF THE DRAWINGS

FIGS. 1-4 illustrate an example user's perspective of a target subject, shooting environment, high-powered rifle with a telescopic sight and other example aspects of a targeting system implementing various aspects of the present invention, in accordance with some example embodiments.

10 FIG. 5 is an illustration of an example control system, which may be used to assist in implementing some aspects of the present invention, in accordance with some example embodiments.

15 FIG. 6 is a cross-sectional illustration of an example system comprising a 3D position-adjustable firing mechanism for a firearm, as may be used to implement various aspects of the present invention, in accordance with some example embodiments.

20 FIG. 7 is a process flow diagram for example steps that may be taken by a system, such as a hardware and software system, implementing aspects of the present invention, in accordance with some example embodiments.

25 FIG. 8 is a bottom-view of an example projectile which, when launched into a target, serves as a relative location and orientation determining probe, in accordance with some example embodiments.

30 FIG. 9 is a bottom-view of the same example projectile depicted in FIG. 8, in a deployed state, having been launched and embedded into, on and/or about a target material, in accordance with some example embodiments.

35 FIG. 10 is a process flow diagram of some example steps that may be taken by a control system implementing some example embodiments of the present invention.

DETAILED DESCRIPTION OF THE 40 INVENTION

45 The example embodiments of the invention presented herein are directed to new devices, methods and systems for controlling projectiles and, in particular, to advanced targeting and projectile systems and devices, which are now described herein. This description is not intended to limit the application to the embodiments presented herein, which are only examples of the virtually unlimited possible embodiments falling within the scope of the present application. In fact, after reading the following description, it will be apparent to one skilled in the relevant art(s) how to implement the following example embodiments in alternative embodiments, including any possible order, number, combination or other arrangement of any or all aspects, components, sub-components and/or relationships thereof (e.g., smaller and larger scale projectiles, in different projectile forms, such as small caliber, conventional profile bullets and flechettes or large missiles). The following order, number, combination or other arrangement of aspects, components, sub-components and/or relationships are non-limiting.

50 55 60 FIG. 1 is an illustration from a user's perspective of a target subject, surrounding environment, specialized high-powered rifle with a telescopic sight and other example aspects of a targeting system implementing aspects of the present invention, in accordance with some example embodiments. Although the example of a specialized high-powered rifle is provided, it should be understood that this is not exhaustive of the numerous alternative contexts in

which aspects of the invention may be applied and operate. For example, aspects of the invention may be applied to missile launching apparatuses, non-projectile ray-generating weapons, tagging and labelling systems, and other types of amiable systems and devices, such as cameras.

The rifle, scope, targeting system and some environmental elements in this illustration will be repeated in additional figures, below, to illustrate the operation of aspects of the invention over time. In some embodiments, a rifle 101 is trained/aimed in the general area of a subject 103 (e.g., the driver of a truck, as pictured) on a distant roadway 105. A telescopic rifle sight ("scope") 107 magnifies the subject 103 and some of the surrounding area, within its viewing portal 109, which may be enclosed by a cylindrical housing 111 and may include a collimating lens assembly and/or electronic viewfinder display features, which may themselves be collimated and variable, and cover or augment the entire field of view of the viewing portal 109 in some embodiments, and will be discussed in greater detail below with reference to this and other figures. In some embodiments, the electronic viewfinder display aspects of the present invention are capable of creating variably-placed, -sized and -shaped images, including but not limited to virtual objects, such as an image of a reticle and/or potential point-of-impact (a.k.a., "impact point") indicators, such as indicating dots and other indicator aspects, which images and/or virtual images may be instantaneously placed, moved, morphed, colored, provided with active lighting ("glow") or otherwise modified. In any event, a more standard, physical reticle with crosshairs 113 may, alternatively or in addition, in some embodiments, also be included, and may or may not itself be reflecting or collimated to ensure or correct for proper alignment and parallax in target sighting. Crosshairs 113 converge at a point initially generally corresponding with a point of impact of a projectile to be fired from the rifle, but the convergence point may be subject to adjustment to account for wind, range, angle/drop vector and other ballistic and/or environmental factors, such as those mentioned above, in some embodiments. An electronically-actuated variable mounting 115 permits the adjustment of the horizontal and vertical position of the viewing portal 109 and/or the crosshairs 113, and may also allow adjustment of the rotational angle of the scope as may be required for the scope to remain viewing at least part of a selected target, as will be discussed in greater detail later in this application with respect to certain embodiments, but this aspect need not be included in all embodiments of the invention. Alternatively, a partially or entirely artificial image viewfinder or other display, such as, but not limited to a light-emitting diode (LED or OLED) or other electronic/photonics display aspect(s), in some embodiments, may be used to create images in the viewing portal corresponding with a view of at least part of the target environment. In some such embodiments, variably-angled sensors or cameras may also be used in place of scope lenses and variable mounting 115 may not be required.

A system including control system unit 117 (which may be a control system comprising computer hardware and software, as discussed in reference to FIG. 5, below), may permit the actuation of servo/motors (also not pictured) within the mounting 115, enabling such angle, horizontal and vertical adjustments to the mounting 115 and/or display image output of the viewing portal 109, in some embodiments of the invention. In some such embodiments, the control system may make any of the adjustments required by a particular implementation of the invention. Preferably, electrical leads 119 allow electronic signal and command

communication between the control system unit 117 and mounting 115 and viewing portal 109. Electrical leads 121 further allow electronic communication between the control system unit 117 and various finger- or thumb-actuated user input controls 123-127. Although local, electrical leads are shown in the example provided in the figure, it should be understood that any method of signal and command communication may alternatively be used, including but not limited to electronic or electromagnetic (such as radio frequency) methods of such signaling and communication known in the art. In addition, although the control system unit 117 is shown as physically attached to the rifle and/or other aspects of the system, the control system unit and user controls may be located anywhere where they may make the commands and communications necessary to carry out the aspects of the invention discussed in this application. A remote control unit and/or user controls, and non-human rifle support and control actuation system, along with live feedback from sensors and/or cameras, may also, or alternatively, be used.

The stock or barrel of rifle 101 may be rested on a stabilizing support, in some embodiments. For example, in some embodiments, rifle 101 may be rested on sandbags 129. In some embodiments, rifle 101 may be rested on any suitable support for resting the rifle and enhancing physical stability, such as a tripod, or other stabilizing prop, and/or the shooter's arm (not pictured). A bolt action 131 and optional manual reloading bolt lever 133 may be used for chambering cartridges and actuating a firing mechanism, including a firing pin and barrel, in accordance with aspects of the present invention. In some embodiments, such a firing mechanism is angle-variable. One example of one form of angle-variable firing mechanism, in which the control system unit 117 controls adjustments of the angle of at least part of a firing mechanism, is provided with respect to FIG. 6. In some such embodiments, those adjustments are made relative to a part of a firearm other than the firing mechanism. In other words, in some embodiments, at least part of the firing mechanism of a firearm may be aimed by changes in its angle relative to an environment, and those changes in angle are different from changes in angle of another part of the firearm. As will be discussed with reference to FIG. 6, such a firing system may be controlled in its vertical and horizontal position as well as its rotational angle by its own instantaneously adjustable servo/motor mounting(s), as controlled by the control system unit 117, in some embodiments. In some embodiments, control system unit 117 generally will instantaneously match the angle of the barrel of the rifle to create a ballistic path that will coincide with at least one point(s) of impact(s) indicated by an impact point indicator generated in the viewing portal 109, in some embodiments. Such point(s) of impact(s) may be selectable by a user for editing in some embodiments. In some embodiments, such point(s) of impact(s) and may be plural and separately created and adjusted, as will be discussed in greater detail below. As also will be described in greater detail below, control system unit 117 may also cause such point(s) of impact(s), their set indicators (which will be discussed in greater detail below) and barrel aiming angles to remain fixed (or appear to remain fixed) in their position(s) with respect to an external reference point or frame of reference in the surrounding environment. In some embodiments, the control system unit 117 may maintain those position(s) with respect to an external reference point or frame of reference in the surrounding environment by counteracting and/or addressing movements with respect to such at least one such reference point or frame. In some

embodiments, the control system unit 117 maintains those position(s) by tracking motion of at least part of a firing mechanism relative to an external reference point or frame of reference in the surrounding environment with inertial change sensors. In some embodiments, the control system unit 117 maintains those position(s) by tracking motion of at least part of a firing mechanism relative to an external reference point or frame of reference in the surrounding environment with sensed and tracked environmental reference points. In some such embodiments, the control system unit 117 also plots projections of anticipated future movements of at least part of the firing mechanism, based on current movements of at least part of the firing mechanism. In some such embodiments, the control system unit 117 also plots actions that may counteract such anticipated future movements. As another example, a specialized physical probe may also be deployed into the target environment, serving as that point of reference for the targeting system, with other impact point indicators and other target-relevant display information presented with a location, if applicable, relative to it. In some embodiments, such probes are also projectiles, which can be fired and planted within at least part of a surrounding environment. Exemplary probes 801 and 901, which may be projectiles in some embodiments, are discussed in greater detail below, in reference to FIGS. 8 and 9. As discussed in greater detail below, object-scanning and location-assessing sensors comprised in or comprising the targeting system may also assist the system in the relative positioning of potential impact point indicators, augmenting the appearance of target features, or other aspects of the invention. For example, in some embodiments, such sensors may include hardware generating probing electromagnetic signals. In some embodiments, such sensors may include cameras. In some embodiments, such sensors may include other imaging hardware. In some embodiments, such sensors may include other scanning hardware. In some embodiments, such sensors include range-finding hardware.

The following is a discussion of some of the ways in which a system according to aspects of the present invention may be used by a shooter to separately acquire and fire upon a target with high precision, while eliminating or reducing many external factors that otherwise might threaten accuracy. First, as shown in FIG. 1, a user brings the target and at least part of a general surrounding area into the viewing area of the viewing portal 109. It should be noted, however, that the system may sense, image, record and track more objects or other features of the surrounding environment in various embodiments, including the location of points of impact located outside the area visible in the viewing portal 109. At this point, the system 117 need not actuate mounting 115 nor alter the shooting angle of the rifle firing mechanism or part thereof, but the user or system may adjust the scope for windage, range and other ballistic variables as in conventional rifle scopes, and the rifle and scope. In some embodiments, the system may operate in a mode in which it may fire as an ordinary rifle, with making any such scope adjustments or firing mechanism angle and position adjustments. However, provided that the sniper has sufficient time and wishes to eliminate certain accuracy-impacting factors, the user may proceed to additional aiming and target acquisition steps using a system in accordance with some embodiments of the invention. For instance, the sniper may next press the point of impact creation button 123. In some embodiments, point of impact creation button 123 is located within range of a user's index finger when holding a handle of a firearm. In some embodiments, however, point of

impact creation button 123 is located separately from a firing mechanism trigger (not shown), as pictured. However, in an alternative embodiment, a partial trigger compression or "pull" may itself serve to create a point of impact, and a point of impact indicator indicating the location of such a point of impact within a display of the viewing portal 109. Assuming that the user has created such a point of impact and point of impact indicator, we will proceed to discuss the effects of the steps set forth above, in FIG. 2, below.

FIG. 2 is an illustration from the same perspective of the same target, shooting environment, high-powered rifle with a telescopic sight and other aspects of a targeting system as discussed with reference to FIG. 1, implementing additional aspects of the present invention. Carrying the discussion forward from FIG. 1, the latest step that the user has undertaken is to introduce a new point of impact and point of impact indicator into the viewing portal, now shown as 209. FIG. 2 illustrates the instant that such a new point of impact and indicator were created, and the location of the point of impact is shown as an illuminated dot 235 which serves as a point of impact indicator. In some embodiments, a concentric circle 237 serves as a point of impact indicator. In still other embodiments, any suitable shape that can be created by a display to illustrate a point of impact may be created as a point of impact indicator by the system. The point of impact indicator, such as 235 and 237, is created by display aspects of the viewing portal 209, such as an electronic display, electronically connected to the control system unit, now shown as 217. The new point of impact indicator may be created and appear directly in the center of the crosshairs, now 213, of the scope reticle and, in the instant of its creation, the point of impact indicator, such as illuminated dot 235, and the convergence of the crosshairs 213 each correspond with a point of impact of a projectile to be fired from the rifle. In some embodiments, as will be discussed in greater detail elsewhere in this application, the control system unit 217 may account for and address all relevant accuracy impacting factors by adjusting the position of at least part of a firing mechanism to ensure the selected location of the point of impact in the environment is hit by a projectile fired by the firing mechanism. In some embodiments, the control system unit may allow the user to address some or all relevant accuracy impacting factors while ensuring that the point of impact in the environment is hit by a projectile fired by the firing mechanism. In some embodiments, the control system unit 217 fires a projectile at a point of impact which has been created only after confirming that accuracy impacting factors have been addressed at the time that a projectile is fired. In some embodiments, such confirming includes updating data related to those accuracy impacting factors. In some embodiments, such data, once updated, is compared to previous data to those accuracy impacting factors and control system unit 217 only fires a projectile at a point of impact if the difference between the compared data is below a particular threshold. In some embodiments, the control system unit 217 fires a projectile at a point of impact which has been created only after confirming the location of the target. In some embodiments, such confirming the location of the target may be carried out by scanning the target, determining its location. In some embodiments, control system unit 217 only fires a projectile at a point of impact if the difference between the most current scanned location of a target is within a particular threshold distance of a previously scanned location of a target. In some embodiments, the control system unit 217 fires a projectile at a point of impact which has been created only after receiving a firing command from a user.

Continuing with an exemplary method embodiment illustrated in FIG. 2, due to user or environmental factors, however, such as breathing, hand shake, heartbeat, loss of grip, nudging, or support subsidence, for example, just before creation of the point of impact and point of impact indicator(s), both the reticle crosshairs 213 and the point of impact indicator(s) have, at least temporarily, been placed by the user slightly off target, to the upper-left-hand side of the of the intended target, the driver of the truck (or part thereof), rather than on or closer to the target's vicinity.

According to some embodiments of the present invention, in creating and maintaining the point of impact and point of impact indicator, additional aspects of which will be discussed in greater detail below, a system, including but not limited to the control system unit 217, may account for and apply ballistic and other projectile path correction functions to correct for or address any or all of the factors affecting or potentially affecting the accuracy of the point of impact indicator at indicating a point of impact of a projectile on a target, if and when such a projectile is fired from the rifle. The potential influence of such factors may be sensed by sensors (not pictured) which feed data to the system, such as, but not limited to, wind velocity, altitude, shot angle (and corresponding gravity vectors causing projectile drop over the range of a shot fired), barometric pressure, air temperature, humidity, environmental nudging or hand shake—such that position correction and/or intercept algorithms and/or functions may be applied to actuators controlling both the angle of at least part of the firing mechanism (such as a firearm barrel) and the scope, as necessary to maintain firing capability on a point of impact and maintain the point of impact indicator and target within the field of view of the scope. However, preferably, at this stage (where the point of impact has been created but not yet set), human and other environmental movement variables are allowed to continue to move the scope, reticle and point of impact indicator. In some embodiments, the system adjusts only the firing mechanism and barrel angle to maintain a set point of impact at the location corresponding with the new impact point, as it may move with the user's hand or other aiming movements, at this stage. This embodiment will be further illustrated, and discussed in greater detail, with respect to later figures.

To aid the system in counteracting gravity vectors causing projectile drop over the range of a shot fired, a specialized form of projectile may also be used, which eliminates or greatly reduces the increasing rate of bullet drop over the flight path of most ballistic projectiles unpowered during some part of flight. Specifically, such a projectile includes lift-creating elements, at least one of which creates a drafting effect on another element, blocking or reducing some of the lift-producing airflow on that another element. As the projectile experiences drag in flight, and reduces its speed, at later points in its flight, the influence of gravity is more greatly offset in such a projectile, by increased airflow and lift on that another element. To maintain fixed, as opposed to spinning, airflow elements, an internal gyro aspect, which may spin within a housing including such airflow elements, may be included, which gyro may be caused to spin by a rifling or other spin-inducing element of the firing mechanism and/or projectile, increasing the projectile's stability. For rifling to induce such spin, access port(s) and/or access grooves in the housing may be included, allowing rifling to engage the gyro unit, or some tab or aspect thereof, to cause it to spin, while straight-line leveling grooves engage the lift-producing elements, or another housing element, to produce rotationally stabilized, or level flight in the housing.

Turning back to the embodiment illustrated in FIG. 2, the user may next choose to "set" the location of the point of impact indicated by the point of impact indicator, for example, using the impact point set button 225. If so, the current location of the point of impact and its indicator (relative to the target environment, or represented target environment) would become fixed, in some embodiments, with reference to the shooting subject- or system-surrounding environment. In some embodiments, the current location of the point of impact and its indicator may become fixed on the target, even if it moves, by tracking and location projection hardware controlled by the control system unit 217. In some embodiments, such tracking is aided by "painting" the subject with an electromagnetic beam generated by beam projection hardware controlled by the control system unit 217. In other embodiments, such tracking is aided by another tracking, projection or intercept hardware or methods. In some embodiments, such hardware may be external to, and in a position different from the remainder of the targeting system (e.g., within a reconnaissance drone or satellite, or landed sensor). As mentioned above, some of those tracking methods are treated in greater detail below, in reference to FIGS. 8 and 9. However, because the point of impact and its indicator(s) has been placed in an off location, due to user and/or environmental factors, the user may instead wish to cancel the point of impact and its indicator(s), using a point of impact cancellation button 227. In some embodiments, depressing point of impact cancellation button 227 returns the system to the state shown in FIG. 1, such that the user can again attempt the correct placement of a point of impact and its indicator on the target. Alternatively, the user may instead tweak the placement of the point of impact to further set it, by using point of impact vertical and horizontal adjustment controls, such as vertical point of impact location adjustment knob 245 and horizontal point of impact adjustment knob 247, respectively, to better set the location of the point of impact and its indicator(s). In some embodiments, depressing the point of impact cancellation button 227 at any point may reverse the previous step entered by the user in the system, even if the previous step was not creating or setting a point of impact and its indicator(s). Supposing that a user has not depressed the point of impact cancellation button 227, the user may, for example, turn the vertical point of impact location adjustment knob 245 clockwise, causing the control system unit 217 to adjust the point of impact and its indicator downward, and may turn the horizontal point of impact location adjustment knob 247 clockwise, causing the control system unit 217 to adjust the point of impact and its indicator rightward. The user may continue making such adjustments, or counter-adjustments, until the point of impact and its indicator(s) are located and displayed by the control system unit 217 and its connected display at the same vertical and horizontal position the target.

Assuming that the user has successfully created a point of impact and its indicator(s) on or near the subject, as desired, using the steps and adjustment process discussed immediately above, the figures below address further aspects of the present invention.

FIG. 3 is another illustration from the user's perspective of the same targeting subject, shooting environment, high-powered rifle with a telescopic sight and other aspects of a targeting system as discussed with reference to FIGS. 1 and 2, but at a later point in time, and implementing additional aspects of the present invention. In the point in time shown in FIG. 3, user and/or environmental variables have caused the rifle 301 to be further moved with reference to the target

driver of truck 303. Specifically, the stock and handgrip 339 and 341 (each of which are closer to the sniper's chest and rifle-actuating hand than the pivoting point 343 of the rifle 301 on the sandbags 329 on which the rifle is resting) may have been budged slightly upward and to the right, from the perspective of the figure. That movement caused the scope, which is closer to the pivoting point of the rifle on sandbags 329, to shift its angle, and point more to the left and downward. As shown in the figure, the system nonetheless maintains the new point of impact and its indicator(s), now 335 and 337, in their set location relative to the target and/or surrounding environment, which may, as mentioned above, be accomplished with the aid of additional hardware, such as a location beacon or probe, inertial change detection or target movement and tracked position projection, or other methods of sensing the movement and the attendant change in position of the scope relative to that target and set point of impact, and moving the point of impact indicator as it appears within the scope to remain indicating its correct placement on the target, within the surrounding environment. In addition, the system may actuate the firing mechanism position (including the barrel, in some embodiments) to shift it vertically and horizontally and/or in alter its angle such that a projectile fired from the rifle would have a point of impact corresponding with the location of the new point of impact and its indicator(s), relative to the target and/or the surrounding environment also including any instantaneous adjustments necessary for any other accuracy impacting factor, as well as the movements discussed above, as may become necessary by changes or introduction of such factors. In the preferred embodiment shown in the figure, the system did not, however, completely counteract the movement using variable mounting 315 to alter the location of the scope housing and reticle and, in some embodiments, such a mounting may have restricted actuation to address certain but not all accuracy-affecting factors. In some embodiments, such a mounting may be fixed and not actuatable. In some embodiments, such a mounting may be actuatable only for general use and initial set-up of the scope on the rifle (which may be prior to the targeting activity, and therefore address general factors but not more immediate, dynamic user and environmental factors). For example, prior to training the rifle and scope on a particular subject, the user and/or system may adjust the scope using variable mounting 315 to address the influence of elevation, humidity, air pressure, and windage, but hand and body movements impacting the rifle, and even more subtle influences such as those caused by hand shake or heartbeat, and other environmental collisions with the rifle, may be permitted to move the scope generally.

Accordingly, the rifle scope, now shown as 307, generally has been allowed to shift and change its angle with the user or environmental movement discussed above, and now points, along with its reticle, downward and to the left of the subject, rather than directly at it. Nonetheless, due to the active, instantaneous maintenance of the set point of impact and its indicator(s) appearing at the location of the target, counteracting the present and/or future projected influence(s) of accuracy-affecting factors on the indicator and firing mechanism, a user firing the rifle at any time after setting a new impact point and indicator will result in firing a projectile that will accurately impact the subject location, despite those otherwise accuracy-impacting factors. By allowing rifle movement to continue moving the scope, and altering the view in the viewing portal, at the same time as maintaining the point of impact, its indicator(s), and at least part of the firing mechanism, however, the user is able to continue scanning and evaluating more of the environment,

and may set additional point(s) of impact, and indicator(s) thereof, in new locations. In some embodiments, such additional point(s) of impact may be selected for a rapid, simultaneous or other pattern of execution by firing of projectiles at such additional points of impact. In some embodiments, a firearm and control system controls multiple firing mechanisms, enabling such simultaneous execution. This embodiment is versatile and timely, while maintaining high accuracy.

10 Some methods discussed above enable a user to, in effect, take a projected, trial shot at a subject within an environment, evaluate its effectiveness, and then execute it only if satisfied. Prior to this invention, shots needed to either succeed or fail, with one, actual take often with undesirable, irreversible consequences. Furthermore, some methods discussed above enable a user, in effect, to adjust an errant trial shot with separate controls, not subject to the vagaries of a more ordinary shooting process, and execute it once the errant shot is corrected.

15 In other embodiments, the scope 307 itself may continue to indicate the point of impact by moving, along with the actuated barrel, to counteract any and all user and environmental factors impacting accuracy—rather than remain fixed with respect to, and moved by, some user or environmental factors, as in some embodiments discussed above. In such embodiments, by selecting a point of impact and its indicator(s) with the aide of the system, crosshairs themselves, or some part thereof, may change shape, color, active lighting, or other indicating characteristics to signify that such a point of impact has been created. Such indicating characteristics, but of a different nature, may separately indicate additional point(s) of impact and the setting or priority status(es) thereof (for order of execution by the system), and additional reticles may also be added, to 20 address those additional point(s) of impact and their indicators, in which case the scope may follow (centered on) the latest new point of impact and its indicator, or highest priority point of impact and its indicator(s), with a corresponding reticle, instead of or in addition to another point of impact and its indicator or component thereof, such as those discussed above, unless and until the setting of another point of impact has begun.

25 Assuming that the user has not yet executed a command to the system (e.g., by full trigger pull) to execute the point of impact that was set and shown by the point of impact indicator(s) 335 and 337, the user may, of course, cancel the point of impact or tweak its location, using the user controls as discussed above. However, the user may also choose to set an additional point(s) of impact and indicator(s), aspects of which will be discussed in greater detail with reference to FIG. 4, below.

30 FIG. 4 is another illustration from a user's perspective of the same targeting subject, shooting environment, high-powered rifle with a telescopic sight and other aspects of a targeting system as discussed with reference to FIGS. 1-3, but at a still later point in time, and implementing additional aspects of the present invention. In FIG. 4, an additional point of impact and indicator(s) thereof have been created and set, shown by point of impact indicator dot 449 and surrounding concentric circle 451. A user has used the process discussed above, with respect to creating the previous point of impact and its indicator(s), which still exist and are now shown as 435 and 437, to create the additional point of impact and its indicator(s) shown as 449 and 451. More specifically, the user has created and set the additional point of impact and its indicator(s) at a location corresponding with a point of impact at the front, right tire of the truck 403,

from the perspective of the driver, near the edge of the road 405 and a cliff 453 descending into a body of water 455.

If the user then chooses to execute one or both points of impact, the system would first cause the point of impact selected for first execution (the highest priority point of impact) to be hit with a projectile, by actuating the firing mechanism as described above for maintaining aim (including offsetting all environmental and user accuracy-impacting factors) and firing upon ("executing") that point of impact. If the user then commands the system to execute the point of impact selected for second execution (the next-highest priority point of impact), the system would then actuate the firing mechanism to cause a projectile to hit the second point of impact, e.g., by repositioning the barrel (aiming it) to do so, accounting for all factors impacting accuracy. In some aspects of the present invention, the system may rapidly execute firing upon each point of impact without pausing to allow the rifle to settle after recoil, and further counteract the impact of recoil as another accuracy-impacting factor. But in other aspects, the system may pause to allow such settling, or, at least, part of such settling, to retain firing capability within the range of possible firing mechanism adjustments. In other embodiments, the system considers movement caused by said firing to be an accuracy impacting factor, and actuates firing mechanism actuators to counteract, or reduce the effect of, that movement. Different modes may be available to permit the user to fire upon all impact points set, or to "double-tap" or otherwise produce a close grouping, coverage of possible locations of a target, or other patterns of multiple shots with an automatic rifle on or about a point of impact, or series of points of impact, which actions may be executed upon one command (e.g., one trigger pull). But serial execution (one impact point per trigger pull or other command from highest to lowest priority—which may be rearranged by the user) after recoil settling and determining that the point of impact is still within the viewing portal, which may correspond with being executable by the system, may be preferred in some embodiments, and may also be used in executing such patterns, in such embodiments.

The targeting methods and systems set forth in this application may apply equally to a wide variety of other pointing, aiming, targeting and executing activities, including, but not limited to, cameras and electronic tagging or data write/re-write activities. For example, shipment tracking systems and high-speed photography systems may create multiple targeting (other forms of impact points) for focused activities using the same types of controls and a similar GUI (e.g., photographic viewfinder rather than reticle), but for intercepting a point or area with a tracking (scanning, reading, writing) or photographic activity.

FIG. 5 is a schematic block diagram of some elements of a control system 500, preferably incorporating a machine-readable medium, that may be used to implement various aspects of the present invention, other elements of which are depicted in FIGS. 1-4, 6 and 7-10. The generic and other components and aspects described herein are not exhaustive of the many different systems and variations, including a number of possible hardware aspects and machine-readable media that might be used, in accordance with the invention. Rather, the system 500 is described here to make clear how aspects may be implemented.

Among other components, the system 500 includes an input/output device 501, a memory device 503, storage media and/or hard disk recorder and/or cloud storage port or connection device 505, and a processor or processors 507. The processor(s) 507 is (are) capable of receiving, interpret-

ing, processing and manipulating signals and executing instructions for further processing and for output, pre-output and/or storage in and outside of the system. The processor(s) 507 may be general or multipurpose, single- or multi-threaded, and may have a single core or several processor cores, including microprocessors. Among other things, the processor is capable of processing signals and instructions for the input/output device 501, analog receiver/storage/converter device 519, and/or analog in/out device 521, to cause a user interface to be provided or modified for use by a user on hardware, such as, but not limited to, physical human hand tracker and other human body part interface controls (e.g., 3-D hand sensor, object emulator, joystick control, sight or scope adjustment dials) and/or a personal computer monitor or terminal monitor with a mouse and keyboard and presentation and input software (as in a GUI), rather than or in addition to electronic/photonic scope or sight aspects, as discussed in reference to other figures in this application.

For example, a "window" presentation user interface aspect may present a user, such as a sniper or other firearm user, with a reticle and/or environmental image, remaining scope readouts or display output, with selectable menu options in a GUI, to select settings for targeting and execution, such as creating, cancelling and adjusting new points of impact or the counteraction or other treatment of factors impacting the accuracy of a firing mechanism (e.g. by actuating firing mechanism actuators that control the position of at least part of a firing mechanism), as discussed in greater detail elsewhere in this application.

As another example, such a "window" presentation user interface aspects may present a user with the option to target or gesture with respect to particular locations of visual emulations of a model or photographic subject, based on live feedback, such as imaging and the detected movement of painted or edge/boundary detected targets within a collateral medium or material. As mentioned above, a wide variety of sensors or auxiliary probes may be used to aid in detecting, defining and even imaging targeted objects or parts thereof ("targets"). As another example, the user interface and hardware may allow a user to manipulate a virtual object that may translate movements into control input matching or related to those movements in real time, and with reference to a live model depicted on a computer monitor and presenting instantaneous information from a radar or sonar or Nuclear Magnetic Resonance Imaging ("MRI") or X-ray radiographic (e.g., CAT scan) machine, which may allow a user to create an activity or apply physical force or energy to particular areas of a target, in particular series, locations, shapes and sizes or pulses and pulse rates to substantially cut or ionize matter, which size and shape may be given a hardness of edge, tolerance, and strength, all individually controllable by a user, and which may be provided as feedback to the user by acceleration of the virtual object, either by an actuatable effigy of the shape, size, position, resistance and weight of the virtual object and its controls, or by tactile stimulus (e.g., ultrasound and/or radiative feedback). A virtual object or other tool may include a shaped cursor which may be semi-transparent, and may allow the user to plan and view a portrayed path for the planned future action, for example, a planned flight path for a fired projectile, or, as another example, a robotically actuated physical movement, such as surgical lancing or other subject manipulation, before it is actually implemented on a subject (which execution can be done in parts or degrees or completely, with a separate, later command to the system). This manipulatable path planning may be done with

a cursor or other display, such as a computer monitor, or depiction/control hardware and techniques (e.g., 3-D physical contour, camera array projection, cutting, shipment tracking plan, or manipulation emulation device). In any event, a user may create a path of planned movement, shooting or a shooting series, tracking protected subject location or path intercept or other activity or other manipulation by programming such a path and/or by first executing the path in virtual or real space and, optionally, reviewing a depicted path based on that execution, and, if satisfied with the characteristics of the movement(s) of the executed path (e.g., direction(s), length(s), instance(s), location(s), coverage(s), breadth(s), pressure(s), actual or real tissue reaction(s), size(s) of lancing or projected lancing, or blunt instrument trial or projection of where lancing or other actuation will take place), all of which characteristics may be displayed numerically or graphically as an attribute of a depicted path in a display as a "Planned Path," representation, the user may then choose to have the path executed. Some such embodiments are discussed in greater detail elsewhere in this application. In some embodiments, before choosing to execute the path, a user may choose to save a file composed and capable of executing the characteristics of the movement on the system. In some embodiments, the user may elect to modify individual, several or all characteristics of the path over any part of the path's progression (for example, by creating or manipulating segmentation tools such as anchor points along the path), again may choose to save such a file comprised of such information, and again may choose separately to execute the path, which may be executed at different speeds along the path or even with a graduated and/or matched acceleration device, such as a throttle for the path's execution speed (using any possible units/time) which may be stopped at any time during observation of the movement. The system may automatically, or at the user's direction, adjust the path or path segments for unintended hand tremor by smoothing or substituting more graduated curves and movement accelerations along progressions or as to characteristics of the path. The system may automatically, or a user may direct it, to generate reactive or protective radiation in greater, lesser or other amounts that better interfere and protect against ionizing radiation, for protected collateral areas, as well, as another example, based on live feedback concerning the amount of protection actually occurring through interference, as sensed by the system, and/or based on physical models, including refraction models.

The processor(s) 507 is/are capable of processing instructions stored in memory devices 505 and/or 503 (or ROM or RAM), and may communicate via system buses 575. Input/output device 501 is capable of input/output operations for the system, and may include and communicate through numerous input and/or output hardware, and numerous instances thereof, such as, but not limited to, a computer mouse, touch screen, flat panel display, collimating light-augmented scope, and pixel arrays, including a pixel array with differently addressable and separately (or in any progressive or other sub-group) scannable and projectable pixels, system element position sensors and actuators (as in example system for a firearm mechanism 511, which may be the system described in FIG. 6, but should be understood to include such actuators and sensors for carrying out the capabilities described aspects of the invention described in that figure), firing mechanism position sensors and actuators (also as in example system for a firearm mechanism 511), MRI machine, X-Ray radiography device, robotic actuator(s), magnetic field creators or modifiers/oscillators

(and magnetically-actuated, locatable particles, such as nano-particles, or manipulation devices that are systemically or locally available in patients, e.g., nano-particles with abrasive surfaces that may spin, expand, grab, cauterize through electric charge, in an oscillating magnetic field and that may also react to markers on targets, available through injection into the patient), communications antenna, electromagnetic radiation source(s), keyboard, networked or connected second computer, camera or scanner, a multi-tiered information storage device (including its actuators and read/write apparatus), mixing board, real-to-real tape recorder, external hard disk recorder, additional movie and/or sound editing system or gear, speakers, external filter, amp, preamp, equalizer, computer display screen or touch screen. It is understood that the output of the system may be in any perceptible form. Any such display device or unit and other input/output devices could implement a program or user interface created by machine-readable means, such as software, permitting the system and user to carry out the user settings and input discussed in this application. Input/output device 501, memory device 503, storage media and/or hard disk recorder and/or cloud storage port or connection device 505, processor or processors 507, analog receiver/storage/converter device 519, analog in/out device 521 and analog/digital hybrid or other combination device 523 are connected and also able to communicate communications, transmissions and instructions via system bus(es) 575. Storage media and/or hard disk recorder and/or cloud storage port or connection device 505 is capable of providing mass storage for the system, and may be or may include a computer-readable medium, may be a connected mass storage device (e.g., flash drive or other drive connected to a U.S.B. port or Wi-Fi) may use back-end (with or without middle-ware) or cloud storage over a network (e.g., the internet) as either a memory backup for an internal mass storage device or as a primary memory storage means, or may simply be an internal mass storage device, such as a computer hard drive or optical drive. Generally speaking, the system may be implemented as a client/server arrangement, where features of the invention are performed on a remote server, networked to the client and made a client and server by software on both the client computer and server computer.

Input and output devices may deliver input and receive output by any known means, including, but not limited to, the examples shown with respect to examples 517, including, but not limited to, example system for a firearm mechanism 511, camera(s) and/or optical sensor(s) 513, separate local computer 515, and example internet servers 509. The input managed and distributed by the system may be any representational aspect or signal or direct impression captured from any sensed or modeled activity, and may be taken or converted as input through any sensor or carrier means known in the art. In addition, directly carried elements (for example a light stream taken by fiber optics from a view of a scene) may be directly managed, manipulated and distributed in whole or in part to enhance output, and whole ambient light information may be taken by a series of sensors dedicated to angles of detection, or an omnidirectional sensor or series of sensors which record direction as well as the presence of photons sensed and/or recorded, and may exclude the need for lenses (or ignore or re-purpose sensors "out of focal plane" for detecting bokeh information or enhancing resolution as focal lengths and apertures are selected), only later to be analyzed and rendered into focal planes or fields of a user's choice through the system. For example, a series of metallic sensor plates that resonate with or otherwise detect photons propagating in particular direc-

tions would also be capable of being recorded with directional information, in addition to other, more ordinary light data recorded by sensors. While this example is illustrative, it is to be understood that any form of electromagnetism, compression wave or other sensed phenomenon may include such sensory, directional and 3D locational information, which may also be made possible by multiple locations and/or angles of sensing, preferably, in a similar or measurably related, if not identical, time frame. The system may condition, select all or part of, alter and/or generate composites from all or part of such direct or analog image transmissions, and may combine them with other forms of image data, such as digital image files, if such direct or data encoded sources are used. Specialized sensors for detecting the presence of interference or resonance of radiation of any type, and imaging the sources or capturing the forces applied based on the known characteristics of waves and electromagnetic radiation in particular, may also be included for input/output devices. Sensors that permit the triangulation or triangulation of light sources, to determine subject and subject environment location and range information, may also be used, and the system may "paint" any part of that subject or environment with electromagnetic, radiative heating, or other markers to ease tracking, targeting, and counteracting environmental/system relative shifts and rotations with the further use of sensors detecting such markings, as discussed in other parts of this application. A direction-indicating beacon may also or alternatively be planted in the surrounding environment to ease these system activities and general system position and subject tracking assessment, including, but not limited to, subject, target and system position projection, in the environment. In this way, impact points may be placed and maintained relative to the subject itself, if marked, or the environment in general.

While the illustrated system example 500 may be helpful to understand the implementation of aspects of the invention, it is to be understood that any form of computer system may be used—for example, a simpler computer system containing a processor for executing instructions and a memory or transmission source. The aspects or features set forth may be implemented with, and in any combination of, digital electronic circuitry, hardware, software, firmware, or in analog circuitry or associational storage and transmission, any of which may be aided and carried out with external hardware and software, optionally, by networked connection, such as by LAN, WAN or the many connections forming the Internet. The system can be embodied in a tangibly-stored computer program, as by a machine-readable medium and propagated signal, for execution by a programmable processor. The method steps of the embodiments of the present invention may be performed by such a programmable processor, executing a program of instructions, operating on input and output, and generating output. A computer program includes instructions for a computer to carry out a particular activity to bring about a particular result, and may be written in any programming language, including compiled and uncompiled and interpreted languages and machine language, and can be deployed in any form, including a complete program, module, component, subroutine, or other suitable routine for a computer program.

FIG. 6 is a cross-sectional illustration of an exemplary system comprising a position-adjustable firing mechanism 601 for a firearm, as may be used to implement various aspects of the present invention. The cross-sectional plane is vertical and bisects the barrel and remaining firing mechanism as they would appear if the firearm in which they are installed was in firing position, as shown in FIGS. 1-4,

creating a view of the right-hand side of the two bilaterally identical halves of the barrel and each other firing mechanism component, with the exception of one component, (a spherical striker, 607) to ease its presentation, is a simple side-view of that part.

A hammer 603 may be included and may be force-biased and caused, upon a shooting execution movement (which may be electronically commanded and/or physically caused) to release stored energy from that force biasing and strike a 10 preferably semi-spherical concave intermediate gear 605 which is physically interfaced with an abutting convex curved, and preferably spherical, striker 607, via gear teeth, such as those shown as 606 and 608. A firing operation embodiment, using the firing mechanism described in this 15 figure, is as follows. When stricken by intermediate gear 605 (itself stricken by hammer 603), striker 607 then, in turn, strikes firing pin 609, which may strike a loaded cartridge 20 in igniting an accelerant and causing a projectile within the cartridge to fire down a rifled barrel 613. Preferably, the magnetic material creating the dipole in spherical striker/gear 607, and shown by groups of negative and positive signs (discussed further, below, and such as those negative and positive signs appearing as, respectively, 610 and 614) 25 is sorted, maintained or reinforced in its dipole position by the striking action—for example, by a heavier positive side of dipole elements.

Any number of physical and electronically mediated, 30 systematically controlled trigger and firing mechanisms may also, or alternatively, be used, to implement various aspects of the present invention. But preferably, a mechanism, which may change the rotational position as well as horizontal and vertical position of at least the firing barrel component of the firing mechanism is used. In the preferred embodiment 35 detailed in FIG. 6, the rotational angle of the barrel may be altered in unlimited degrees by the rotational actuation of spherical striker 607, which, owing to its electromagnetic dipole, may be rotated without structural contact by electromagnetic actuators 615, which are controlled by the 40 control system. Actuators 615 are shown in the figure with equal net negative charges, leading to stabilizing force on the balanced (unrotated) position pictured of striker 607. Additional sensors (not pictured) may relay rotational position and/or other barrel position data, or data from which 45 rotational position may be extrapolated, back to the system, to aid in the system's determination of rotational angle and other barrel position adjustments that will result in a point of impact of a projectile corresponding with an indicated impact position selected (given highest priority) for firing. By causing striker 607 to rotate (in any spherical rotation direction and amount of rotation dictated by the system) 50 omni-directionally operating gear teeth, such as those pictured as 608, of striker 607 interface with complementary omnidirectional gear teeth, such as those pictured as 606, of intermediate gear 605, the system may control and adjust the barrel rotational position by unlimited degrees, in 3 dimensions, as well as slightly shift the barrel fore and aft in the directions of its length, and move the end of the barrel upward and downward, by various degrees. As striker 608 55 rotates, and its teeth 608 interface with and climb the teeth 606 of intermediate gear 605, the side of the barrel proximal to hammer 603 moves horizontally, vertically and by rotational position. Servo/motor actuatable (e.g., by solenoid) barrel movement pistons 617 are mounted to the body of the 60 rifle and connect to the barrel by rotatable (preferably, hinged) bracing joints 619, which may connect with the barrel by a ring-shaped clasp 620, in which the barrel fits

but, in some embodiments with fore and aft barrel movement, may slide and rotate (e.g., with the use of sprung bearings or a gasket), as necessary, fore and aft to accommodate rotational and shifting movement of the barrel, further enabling rotational and horizontal and vertical barrel movements and at least semiautomatic or bolt action chambering of new rounds using barrel recoil, gas compression, electronic actuation of actuators or manual bolt operation (each such action is not pictured). Joints 619 and clasp 620 preferably hold the barrel and/or attached chamber and firing pin and its housing from a location or point on the length of the barrel more distal from the hammer end than the spherical striker, or other rotational direction actuation driver. As another example of a rotational actuation driver, a set of two or more separately actuatable pistons (not pictured), similar to pistons 617 but to the right of pistons 617, from the perspective of the figure, and also connected to a clasp by rotatable bracing joints, may drive the position of the proximal end (facing the hammer) vertically and/or horizontally in varying degrees and, in conjunction with fixation or coordinated actuation of pistons 617, may yield a wide variety of rotational, horizontal, vertical positions of the barrel, as dictated by a control unit of the system. Another such piston may be used, but mounted for fore and aft shifting actuation of the barrel, to accomplish different fore and aft shifting of the barrel. But in combination, pistons 617 (with their slidably attachment joint 619) and spherical gear striker 607 (or the alternate piston embodiments discussed immediately above) permit the system to adjust the barrel to modify shot elevation, lateral position, and bullet path—and each of those types of movements separately or together. In this way, ballistic equations may be dealt with more easily by the system, by isolating variables for alteration, rather than with more complex ballistic equations. In the context of applying a similar mounting for 3-D photography, various angles may be acquired for a photographic subject from one lens, which may be mounted as the barrel is in this example to aid in rapidly acquiring and executing such shots. In another, simpler embodiment, but without all of the firing mechanism positioning capabilities, a single set of pistons, or other positioning actuators (such as those incorporating servo/motors and solenoids) such as those shown as 617 may be used, in conjunction with a rotatable joint, pocket, pivoting point or other physical rotation point (which need not be separately actuatable by the system) may be used in place of the spherical gearing, to accomplish some rotational actuation and even some horizontal and vertical shifting of the barrel, as may be dictated by the system. A wide variety of other rotational and position actuation mechanisms and feedback, including purely electromagnetic actuation, may also be used, though the embodiments discussed are preferred due to the high cost of such purely electromagnetic actuation of all elements, given the high current cost of moving and holding heavy weapons firing components electromagnetically. In the photographic application of the invention, however, more or purely electromagnetic actuation and feedback, such as that discussed for spherical striker 607, may be preferred for all actuators.

Force-loading structure 621 connects the body of the rifle and barrel, and applies force to the barrel in the direction indicated by force-indicating arrow 622, driving and seating the barrel and connected chamber, firing pin 609 and, most immediately, spherical gear striker 607 into gear 605. Straight-line moveable, piston-action mount 605a connects gear 605 to the body of the rifle, providing a secure platform and also applying reacting force in the direction opposite to force arrow 622 to aid in maintaining strong gear teeth

interface for gear 605 and striker 607, by pushing them together. In alternate embodiments, the hammer element may be omitted and the piston 605a or other striking actuator may itself provide striking force to gear 605, striker 607 and/or firing pin. In this instance, a specialized piston and actuatable-rotating armature also may be used, which allows the striking force to be generated in any direction, and more perfectly oppose (be generated 180 degrees from) the barrel and chamber direction, however it may be rotationally actuated at the time of striking—moving gear 605 in a straight-line path direction perpendicular to the tangential plane at the central point of the spherical gear interface. A semi-spherical gear such as 605 with a spherical center located at the distal rotational pivot point of the barrel may, instead, be used (as pictured by alternate gear inner surface shape, teeth omitted, shown as 627), which may aid in creating even opposing force as the gear is actuated. But in that case, the capability for fore and aft shifting of the barrel during rotational actuation will be eliminated unless an additional piston or other actuator for creating fore and aft shifting of the barrel and firing mechanism is used. Alternatively, or in addition, uneven gear teeth angles and thickness may be used, as pictured, to create approximately stable striking force at the point of striking, opposing the direction of the barrel and chamber, for any possible point of spherical gear interface. In any event, the system may use a final (firing strike completed) barrel position, to whatever degree the barrel may shift in each rotational position due to striking action, in determining the nature and degree of barrel position actuation to result in hitting the highest priority impact point with a shot. To allow piston 605a to operate at a radially-centered attachment point, hammer 603, if used, may contain a central slot or cavity, or be comprised of two striking pieces, between which such a piston is seated. If the hammer is omitted, an actuatable striking force exerter may be connected directly to the barrel and/or striker and/or firing pin, and spherical gearing may be implemented without a spherical gear also serving as a striking or strike-transmission element, as it is in the figure. However, such an embodiment may be more expensive to implement, as it would require electrical or more complex mechanical striking assembly, to allow changing barrel position and still exert a sufficient striking force at all such positions.

Turning back to the embodiments shown in the figure, variable striker holders 623 may prevent firing pin actuation until a firing execution is commanded or carried out—serving as a safety and gear engagement maintenance device. For example, holders 623 may retract into pockets 624 by a system or user electronic command or actuation signal, or simply by being overcome by the force of a hammer strike from hammer 603, toward the spherical striker 607. Alternatively, as discussed above, hammer 603 may be omitted, and straight-line only movable piston mount 605a may itself be system- or firing movement-actuable to strike spherical striker 607 and overcome the holding force of holders 623.

FIG. 7 is a process flow diagram for exemplary steps 700 that may be taken by a system, for example, a hardware and software system, such as the system discussed above with reference to FIG. 5, implementing certain user interface and display aspects of the present invention. In step 701, the process begins and proceeds to step 703, in which the system receives or consults any sensor-transmitted or stored data indicating whether a new impact point (“N.I.P.”) button has been newly depressed (meaning that the system has not already taken action on such a depression), such as, for example, the button given as 123, 223, 323 or 423 of FIGS.

1-4. If so, the system proceeds to step 705, in which it creates a point of impact (for example, by storing its coordinates and readying the firing mechanism to aim a projectile at a location corresponding with those coordinates at any time a firing command is given) and its visual indicator(s) as discussed elsewhere in this application. As step 705 and other steps indicate, it is preferred that unless and until this N.I.P. and indicator have been “set” it remains pinned to the intersection of the crosshairs of a reticle (or otherwise in an easily-referenced user-movable position for unset N.I.P.s and indicators within a sight or display, depending on the embodiment chosen). Accordingly, after creating an N.I.P. and indicator, and placing them in the center of the crosshairs for further procedures, the system returns to the start position, 701. If at step 703, however, the system determines that the N.I.P. button has not been newly depressed, the system proceeds to step 707, in which the system receives or consults any sensor-transmitted or stored data indicating whether an N.I.P. “set” button has been newly depressed, such as, for example, the button given as 125, 225, 325 and 425 of FIGS. 1-4. If so, the system proceeds to step 709, in which the system places the N.I.P. and indicator in a set position relative to an observed or representatively displayed target and/or surrounding environment, in the displayed output of a sight (and preferably, the last of these options, because the system may then use inertial indicators such as accelerometers only, and therefore may be cheaper and more practical for use by a sniper). To define targets (such as targeted objects, in some embodiments), if implemented by the system, the user and/or system may identify and/or define subject objects and/or boundaries, colors, shading, or other properties thereof—automatically, or by “painting” or otherwise marking, monitoring (e.g., by comparing live attribute data to data associated with physical models of a subject, and perspective view or other subject attribute information), tracking (same) or indicating them—as discussed elsewhere in this application. In some embodiments, the system maintains a library of objects, or object types, and matches objects scanned in the environment to such objects. For example, in some embodiments, the system may perform confidence-interval matching to determine a likelihood that a scanned object in the environment matches an image of an object stored in that library. Furthermore, in some embodiments, the system may maintain a map of targets within such images of objects. In some such embodiments, the system also maintains classifications of each of such targets, and differently conditions the priority of points of impact corresponding with those targets and classifications. For example, images of human bodies may be maintained in such a library, as well as the location of lethal and non-lethal firearm shooting targets within those images. By matching such images to scanned objects in the environment, such as a real human being, lethal and non-lethal targets may be extrapolated and mapped onto the scanned objects. In some embodiments, points of impact created that correspond with the mapped locations of non-lethal targets may be given a higher priority than points of impact created that correspond with mapped locations of lethal targets and, thus, may be executed earlier by the system. In some embodiments, different projectiles or other measures may be fired at, or otherwise delivered to, points of impact within targets, depending on such classifications of mapped locations. Also as discussed elsewhere in this application, a physical probe or other non-lethal element may be introduced into the target environment or even attached to the target or an object attached to the target, to define the relative position of the target and an impact point

set by the system. As yet another example, additional cameras or other imaging apparatuses (e.g. implementing LIDAR) may aid in range-finding for a target object and its surrounding environment. Such apparatuses may be located anywhere (e.g., aboard fixed positions, motor vehicles, satellites or aircraft), and made a part of the system by wired or wireless networking. Whether or not subject definition is used, preferably, the system actively maintains the N.I.P. and indicator in the position relevant to the embodiment (again, preferably, with respect to the surrounding environment of the system), such that it represents a point of impact of a projectile if fired by the system, from the targeting sight/display perspective of a user of the system, at all times after being set, regardless of system movement, as long as the indicator remains within the view of the sight or display as it, and its matching representation, if applicable, is positioned. Also preferably, if a representative or displayed sight output is used to represent the target subject and/or environment surrounding the N.I.P. and indicator, the system also maintains an accurate representation of that environment in real time, matching the actual user and system view perspective of the actual subject and environment, and, in some embodiments, implements a margin around the N.I.P. and indicator that may be user- or system-variable. To achieve such a margin during motion of the system while still tracking that system motion with an accurate view of the target environment (matching the perspective change due to the movement), the system may increase the viewing space, magnification, or create additional viewing angles (“screens,” “windows” or tabs) or change focal length and/or add magnification transitions, allowing the user to assess the system movement by changed perspective of the environmental representation, while maintaining a relative indication of the position of the set N.I.P. and indicator. Prior to setting an N.I.P. and indicator, however, in any embodiment’s environmental view, changes to match the actual or selected user and/or system view perspective of a subject and/or environment would be made. Also preferably, adjustments to the firing mechanism are also made in real time, to maintain a point of impact of a projectile, if fired, coinciding with the location of an N.I.P. and indicator assigned the highest priority for firing, by the user or system. Rather than have real-time adjustments to the firing mechanism, environmental perspective and set N.I.P. and indicator displayed, however, the system may periodically correct the environmental and/or subject view perspective displayed, and the displayed set N.I.P. location, as will be discussed in greater detail below.

If the system has placed a set N.I.P. indicator for the latest set N.I.P. on the display within a view or representation of the target environment in the sight, according to step 709, or, instead, determined that the N.I.P. “set” button was not depressed, the system may proceed to step 711. In step 711, the system determines whether any N.I.P. indicators have been set by the system, including such indicators that may have been set prior to the possible instance discussed above. If so, the system may proceed to step 713, in which it determines whether N.I.P. adjustments are to be made, for example, based on user input adjusting the position of a set N.I.P., such as by horizontal and vertical position adjusting knobs 247 and 245, from FIG. 2, which may also be axially compressible such that a user may toggle between set N.I.P.s and indicators for adjustment and priority rearrangement, which may also be by separate controls. If such adjustments are being made, the system implements such adjustments by moving the relative position or altering the priority of the N.I.P.(s) selected for adjustment (which may also or alter-

natively be by any other practical method of object selection and movement in G.U.I.s). Whether or not adjustments have been implemented, the system then proceeds to step 717, in which the system may adjust display output to accommodate any shift in position, range, magnification, perspective, settings, sight movement, or any other factor impacting the accuracy or usefulness of representation of the targeting subject and/or target-surrounding environment represented by the display, relative to the viewer's or system's perspective. The system then proceeds to step 719, in which it further determines and implements necessary adjustments to represent the N.I.P. by an indicator in the set location for any set Impact Point within that environment or relative to a targeting subject. As mentioned above, various additional techniques may be implemented to maintain a representative view or other awareness of the targeting subject location, target-surrounding environment and a view of the N.I.P. and indicator.

The system then proceeds to step 721, in which it determines and implements necessary adjustments, as discussed elsewhere in this application, to the firing mechanism such that a projectile fired from the firing mechanism will place a projectile on, or as near as possible to on, the location of any set N.I.P. and indicator with the highest priority within the surrounding environment. If there is no currently set N.I.P. and indicator, the system may treat the intersection of the crosshairs or other reticle or impact point display point, as a set N.I.P. and indicator with the highest priority, and implement the adjustments to the firing mechanism discussed immediately above, with respect to step 721. The system then proceeds to step 723, in which it determines whether a firing command has been given by the system or user. If so, the system causes the firing mechanism to fire. If not, the system returns to the starting position.

FIG. 8 is a bottom-view of an example projectile 801 which, when launched into a target, may serve as a relative location and orientation determining probe, in accordance with some embodiments. In some embodiments, such a projectile may also be referred to as a "smart bullet," meaning that it has components allowing for monitoring and controlling its flight (i.e., steering the projectile in-flight) while also having at least the approximate shape and dimensions of a conventional bullet for firearms. In some embodiments, as will be discussed in greater detail below, example projectile 801 may also aid a user in monitoring ongoing information, such as the location and other changing conditions (including internal conditions) of a target, after striking and implanting itself into, on or about such a target. In some such embodiments, example projectile 801 may aid in follow-up strikes on the target or another, nearby target, or other actions, which may be based on such ongoing information.

As with other projectiles discussed in the present application, example projectile 801 comprises an example outer surface 800, which is generally streamlined in shape (e.g., at least partially rounded), in some embodiments. However, in some embodiments, outer surface 800 comprises movable components and joints that react in particular ways when projectile 801 is launched, in-flight and when embedded into a target material. For example, in some embodiments, surface 800 comprises an example seven (7) moving outer surface components, as well as other internal moving component(s), held within surface 800. The exact number and positioning of such components pictured, while useful, are illustrative and not exhaustive of the many possible different numbers and orientations of surface components. An example positioning of such components of surface 800

when deployed is illustrated in greater detail in FIG. 9, below. It should also be understood that some or all such moving components may be omitted, in various embodiments, while still carrying out the tagging, location and projectile flight, orientation and steering aspects of the present invention. Such moving components aid, however, in projectile flight, mounting and signaling to an external control system (such as example control system 117, and as set forth above in reference to FIG. 5, which, in various embodiments, may or may not be comprised in or, alternatively, comprise targeting systems such as those set forth above in FIG. 1 et seq.), which is capable of communications with projectile 801. To aid in such communications, projectile 801 preferably comprises wireless communications antenna(ae) 803, connected with and able to communicate with both an external control system(s), as discussed above, and, in some embodiments, an internal control system 805, resident in projectile 801. Because projectile 801 comprises multiple antennae, each may indicate its own position, allowing a control system to determine the position of each component comprising each antenna and, therefore, the relative orientation of each component, with respect to each other and a corresponding receiving antenna located on the external control system. For example, by receiving different signals at different angles of propagation, and arriving at different times from each antenna 803, the external control system can assess the relative distance and orientation of each such component, and of the projectile in general. In some embodiments, projectile 801 may, alternatively or in addition, comprise electromagnetic transfecters or reflectors 807, which may reflect probing or otherwise testing signals issued from the external control system. As with antennae 803, reflectors 807 may reflect such test signals at different angles and at different distances, and also with different identifying characteristics, by each reflector selectively absorbing and reflecting different components of such a test signal. For example, a different resonant or retro-reflective mesh or other material 809 may be present in each reflector and/or a differently-angled or varying-depth slit covering them may selectively block different amounts and components of the test signal—as well as reflecting differently depending on the degree to which the components have moved during deployment, indicating the degree and position of surface components during deployment.

To allow such movement of surface components, each component may be connected to the remainder of projectile 801 by hinged joints, such as the examples shown as hinged joints 810. Each of the example seven components of surface 800 are visible in the figure, including a tip component 811, and three sets of one fore and one aft main body component joined together, such as the example shown as 813. In some embodiments, example projectile 801 has an approximately rounded profile and outer surface 800, created by structural components, including fore component 815 and fore component 817, located on or about a leading end 818 of example projectile 801, and aft components, including aft component 819 and aft component 821, located on or about a trailing end 820 of example projectile 801. In some embodiments, projectile 801 has an at least approximately radial symmetry (as in most bullets) about a central, lengthwise axis 822 (which axis is oriented from left to right, in the perspective of the figure). Only two sets of fore and aft components are visible in the figure as part of the outer surface 800—namely, fore component 815, fore component 817, and, to which each is connected, respectively, aft component 819 and aft component 821. Of course, the examples of moving structural components pictured are

merely examples of the virtually unlimited numbers and locations of moving structural components which may be used in smart projectiles falling within the scope of the invention. The exact number of such moving structural components may be fewer or more numerous, in various embodiments. For example, in some embodiments, a single (1) movable (i.e., actuatable) structural component may be included within example projectile 801. As another example, in some embodiments, two (2) movable structural components may be included within example projectile 801. As another example, in some embodiments, three (3) movable structural components may be included within example projectile 801.

In some embodiments, the control unit 805 (if present) may comprise a number of additional subcomponents for detecting and communicating orientation, position, movements and other factors to the external control system. For example, in some embodiments, control unit 805 comprises an accelerometer, for determining movements of example projectile 801, as well as its orientation and position relative to the force of gravity. The control unit may also comprise a gyroscope, which may be a directional gyroscope or gyrocompass, or a form of gyroscope otherwise re-calibrated periodically according to a reference direction. Preferably, such a gyroscope or gyrocompass is damped from movement during deployment, to avoid miscalibration or damage during impact of the projectile. As another example, if the control unit is equipped with a G.P.S., or (for example, with its wireless communications antenna(æ) 803 in communication with G.P.S. satellites), indicating its relative orientation and position, a gyroscope or the control system 805 may be periodically recalibrated to indicate a relative orientation of probe 801 with improved accuracy. Similarly, indications from an accelerometer(s) may be used to cross-check movements indicated by a gyroscope or by electromagnetic test signals of the external control system that interact with antennae 803 and/or reflectors 807 (and vice versa). In some embodiments, the accelerometer(s), gyroscope(s), G.P.S. systems, reflectors and antennae may aid in directing the positioning and orientation of projectile 801 during flight, making projectile 801 a remotely-controlled projectile that can be actively directed to a particular target. For example, using a flight-simulating GUI within the external control system, or an augmented targeting GUI such as those set forth in FIG. 1 et seq., a user may select a desired target, causing projectile 801 to be directed toward it in flight, even if initially launched in a direction away from the target—for instance, by issuing a wireless signal commanding an servo 823 to bend and alter the angle of a stabilizing tail piece 825, from 180 degrees to a more acute angle in the direction of desired movement. Servo 823 may also be a rotationally actuatable servo in some embodiments, allowing the user or control system(s) to maintain a desired rotational orientation during flight and deployment at a target. Any actuator known to those of skill in the art, connected for communications with control system 805, and/or a control system remote from projectile 801 and networked with on-board control system 805, may be used instead of, or in addition to, example servo 823. Similarly, such an actuator may control any active, controllable aerodynamic component of such a projectile known in the art for altering the flight path of a projectile, and tail piece 805 is of course only one example of the virtually unlimited possible aerodynamic components within the scope of this application.

As mentioned above, the dynamic operation of some example components of projectile/probe 801 are treated in more detail, immediately below, in reference to FIG. 9.

FIG. 9 is a bottom-view of the same example projectile depicted in FIG. 8, now shown as example projectile 901, in a deployed state, having been launched and embedded into a target material—namely, example wall 900. As mentioned above, when example projectile 801 collides with a target, in some embodiments, its surface components shift, changing their configuration to become more spread out and rendering communications sub-components (and, especially, any internal components, in some such embodiments) more accessible by an external control system. For example, a fore and aft component pair, including fore component 815 and aft component 819, have raised upward (in the perspective of the figure) and turned on a ring joint 931, that joins them together, as have each of the other two pairs of example fore and aft components of the same form. As a result, in the embodiment pictured, after impact with a target (example wall 900), probe projectile 901 has increased its vertical profile dramatically, stretching out upward and downward, in comparison to the embodiment shown in-flight (example projectile 801). Also, the communications antennae 803 and differentiated reflectors 807 now face away from the target (approximately in the direction of the user, firearm or other projectile launcher, and external control system that launched projectile/probe 901), making them more accessible and easily differentiated via wireless signals (e.g., electromagnetic waves partially absorbed and reflected back from reflectors 807), being a greater distance apart in space. To aid in this spreading action in some embodiments, a central piston (in this case, the housing 904 of control unit 805) moves relative to the remainder of probe 901, in the horizontal direction, toward the target (such as wall 900) with which probe 901 has collided. This will naturally occur as tip 811 impacts wall 900 because the remainder of probe 901 decelerates on impact with the target, while the control unit housing 904 continues moving in the direction of the target, colliding with the inner surfaces of each surface component, spreading them outward. To enable this relative movement, a bungee cord or other elastic element 933 may be comprised in and attached to both the control unit and the remainder of the probe (in this instance, at joint axel 935), which may also comprise conductive wires for electronic communications between the control unit and its communications hardware, sensors and other components controlled by the control system. Elastic element 933 also aids in dampening and limiting that forward movement and destructive potential of housing 904, by creating a reactive elastic force opposing it.

As tip 811 collides with target wall 900, in some embodiments, its sharp profile allows it to pierce the material of the wall and enter it. In some embodiments, a sharper or harder tip material may be used, or a larger launching force may be exerted on projectile 901, to pierce and mount probe 900 in harder, stronger, more robust or more distant materials (e.g., armor). In other embodiments, a softer material or lower launching force may be appropriate for deployment and embedding of the probe into a softer or more flexible material (e.g., clothing of a target person to be probe will be attached and tracked, and future targeting will be defined relative to, as set forth above in reference to FIG. 1 et seq.) To further aid in mounting and embedding probe 901 into its target material, additional barbed piercing connectors 937 are provided, further up the length of the forward arms/surface components, such as 815, such that they swing into, pierce and grip the material of the target as probe 901 expands. In some embodiments, other gripping connectors, such as outer members or sheets 939 comprising small hooks, barbs or microscopic cilia which may affix probe 901

to a target with van der waals forces, may also be included. These embodiments are particularly useful for attaching probe **901** and fixing it in orientation to clothing of a human target; as tip **811** pierces and more deeply anchors probe **901** into a target, additional binding forces with such outer materials is then possible. In any event, as tip **811** pierces the target, the additional piercing connectors and/or gripping connectors naturally swing forward toward the surface of the target as the surface components of probe **901** spread out upon impact and deployment, also piercing or anchoring probe **901** to the target and fixing its orientation relative to the target.

As a result, after the probe **901** is so attached to the target, and fixed in orientation relative to it, and its wireless communications antennae and reflectors become accessible to the external control system of the targeting system (e.g., such as the targeting systems set forth above, in reference to FIG. 1 et seq.), the targeting system then has a probe within the target, fixed in orientation relative to it, defining and indicating to the targeting system a set of three-dimensional coordinates defining all three dimensional space relative to the probe and the targeting system. As a result, the targeting system can set additional, more specific targets within that coordinate system (e.g., non-lethal stopping force can be applied by shots to the target, if so desired, by targeting an immobilizing but otherwise non-vital structure).

In some embodiments, additional hardware may also be included within probe **901**, and controllable by internal control system **805** (which may itself be controlled by commands and communications from the external control system within the targeting system), to increase the number and variety of options for further dealing with the target. In various embodiments, such additional hardware may include: motorized hypodermic needles with drugs held within an attached vessel (e.g., tranquilizers), electric shock-delivering devices, sound-, heat-, light- or gas-generating devices and explosives, or radio beacons, to name just a few possibilities. In some embodiments, probe **901** may include a speaker or two-way communications equipment, for issuing commands or otherwise communicating with a target. Any or all of the above actuators may be actuated by command from a user and/or remote control system or a control system on board example projectile **801** or example projectile **901**, either of which control systems may be, include, or be included within, a control system including computer hardware and/or software, such as example control systems set forth in this application. For example, such a control system may be example on-board control system **805** and/or example control system **500**, discussed in detail above and in reference to other figures. As discussed above, such a control system may include hardware capable of creating and managing a wireless network (via antennae **803**), and thereby conducting wireless communications, e.g., with another control system in a remote location from the projectile **901**. In some embodiments, as discussed above, such wireless networks may be, or include, LAN, WAN and/or the many connections forming the Internet, in various embodiments, as discussed in greater detail throughout this application. (See, e.g., FIG. 5 generally.) More specifically, and as discussed above in reference to FIG. 7, smart bullets and other projectile devices set forth in the present figure may maintain communications via wireless networking with other computer systems and devices. As is widely known in the art, computer systems with wireless networking capabilities are equipped to establish wireless networks, and such capabilities are within the scope of the application.

As explained above, because projectile probe **801/901** is physically fixed in position and orientation to a target material, a targeting system employing such a projectile/probe can define relative distances and positions within said target, and a surrounding environment, with greater precision and greater control, and place or alter impact point indicators in relation to the position and orientation of projectile/probe **801/901** after deployment. Although the example of a physical, non-lethal projectile for defining relative positions of a targeting system (and positioning impact point indicators within a sight and/or display) is provided in detail, it should also be understood that any other system component or method for altering a target material, or an object attached to a target material, may also be used. For example, in one embodiment, a laser or other beam-generating sight (e.g., mounted on the body of the rifle or other launcher of projectiles to be fired by the system) comprised in the targeting system may be used, in which a collimated beam of coherent light or an electromagnetic beam is used to heat, marking, "paint" or otherwise alter a point or region of the target material or an object attached to it. Positions relative to the heated, marked or painted region or point may then be detected (e.g., by light, laser or infrared sensors within the system) to define impact points and display them to a user.

FIG. 10 is a process flow diagram for exemplary steps **1000** that may be taken by a control system, for example, a hardware and software system, such as the system discussed above with reference to FIG. 5, implementing certain embodiments of the present invention. In some embodiments, as discussed above, such a control system may be present within, or at least partially present within, a device for controlling the operation of a firearm. For example, in some embodiments, such a device may be mountable onto a firearm, monitor the motion of that firearm, and control at least some operation of that firearm. In some embodiments, and also as discussed in greater depth above, such a device may incorporate a display, for monitoring the position of one or more possible and/or predicted point(s) of impact of a projectile(s) fired from the firearm, based on a variety of environmental, firearm-related and other factors.

In some embodiments, such a device includes at least one sensor, for monitoring the motion of the firearm within an environment. In some embodiments, such a sensor is a motion sensor, such as any suitable motion sensor known in the art. In some embodiments, such a motion sensor includes a camera. As another example, in some embodiments, such a motion sensor includes an accelerometer. As yet another example, in some embodiments, such a motion sensor includes a range finder (e.g., incorporating RADAR, SONAR and/or LIDAR). In some embodiments, such a motion sensor includes a compass. In some embodiments, such a motion sensor includes a G.P.S. or other beacon-based location and/or orientation determining technology. In some embodiments, any of the motion sensors set forth above determine and communicate a location of the device and/or an attached and/or associated firearm, in three-dimensional space, within a surrounding environment. In some embodiments, any of the motion sensors set forth above determine and communicate a rotational position of the device and/or an attached and/or associated firearm, in three-dimensional space (e.g., based on rotation sensor(s) determining the degree of rotation of the device about 1, 2 and/or 3 rotational axes, relative to an environment surrounding the device).

In some embodiments, such a device controls the operation of a firearm, at least in part, via a firing mechanism

connected for communications with, and actuatable by, the control system. For example, in some embodiments, the control system may be electronically connected for communications with such a firing mechanism, which is control system-actuable via those communications (e.g., incorporating an electronic firing mechanism actuator, which can drive shooting, or arrest shooting, of the firearm on command by the control system). In some embodiments, the control system may be wirelessly connected for communications with such a firing mechanism, which is control system-actuable (e.g., incorporating a wireless firing mechanism actuator, which can drive shooting, or arrest shooting, of the firearm on command by the control system). As one example of such a firing mechanism actuator, such a device may include a control system actuatable trigger, in some embodiments. As another example of such a control system actuatable firing mechanism actuator, in some embodiments, such a firing mechanism actuator may include a firing mechanism safety (such as a safety switch).

In some embodiments, as discussed immediately below, such a device may carry out steps to control operation(s) of a firearm, based on the location of at least one predicted point of impact of such a projectile within such an environment, and/or based on motion of said device and/or the firearm (on which it may be mounted) within said environment and based on a position of said device relative to said point-of-impact. Some examples of such steps are discussed immediately below.

Beginning in step 1001, in some embodiments, the control system may begin by determining whether an onboard power source (e.g., a battery) has sufficient levels to run anticipated operations of the control system (such as those discussed in greater detail, below). If not, in some embodiments, the control system may shut down, sleep and/or return to the start of the process. If sufficient levels of power are determined to be available, however, in some embodiments incorporating at least one display (for presenting a G.U.I., as discussed above), the control system may display certain current user-variable and other settings of the control system. For example, as discussed above, in some embodiments, motion sensors such as those discussed above may monitor motion of the device and/or an attached or associated firearm. In some embodiments, an amount of such movement, and/or an amount of such acceleration, may be set by a user and/or the control system, above which amount(s), the control system will arrest or otherwise prevent firing of the firing mechanism of the firearm (e.g., by activating a safety device or by otherwise preventing the actuation of the firing mechanism.) In some embodiments, such amounts may be referred to as “thresholds” of movement and/or acceleration, above which errant, inaccurate operation of the firearm is prevented. Thus, in such embodiments, the control system may proceed to step 1003, in which it displays the latest user- or control system-set threshold(s) for movement and/or acceleration, discussed above (e.g., on the display, or on a physical dial that indicates such time periods). The user may then adjust the amount(s) of those threshold(s), in step 1005, which is then recorded and implemented by the control system as the new, currently set threshold(s), as indicated in step 1007. In some embodiments, only a motion threshold is included. In some embodiments, only an acceleration threshold is included. In some embodiments, both a motion and an acceleration threshold are included.

In some embodiments, a user-alterable setting may control the time and/or time period in which such monitored motions take place. In some embodiments, such time periods

are measured backward from the time that a firearm is to be fired (e.g., a time when a user requests the firing of the firearm, such as by fully depressing or “pulling” a trigger of the firearm). As will be discussed in greater detail below, in various embodiments, if substantial movement, acceleration and/or inaccurate aiming of the firearm is determined to take place during that time period (such as movements exceeding the threshold(s) discussed above), the control system may arrest or otherwise prevent firing of the firing mechanism (e.g., by activating a safety device or by otherwise preventing the actuation of the firing mechanism.) In some embodiments, such a time period may be instantaneous, or substantially instantaneous. In some embodiments, however, the time period may be set by a user (e.g., by a user control, of a GUI of said device, presenting options for such time period selections.) Thus, in such embodiments, the control system may proceed to step 1009, in which (again, in some embodiments, after displaying the currently user or default or control system set time period, e.g., on the display, or on a physical dial that indicates such time periods) it permits the user to select and set a new amount of time as that time period. The length of that time period is then recorded for implementation by the control system, in step 1011.

As discussed above, in some embodiments, if sensors monitoring movement of the device and/or associated firearm indicate that motion of at least a part of the device and/or firearm exceed the threshold amounts currently set and implemented, during the time period currently set and implemented, at a time when a user (such as a human user, Artificial Intelligence, and/or control system) requests firing of the firearm (e.g., by pulling a trigger of the device or firearm, or otherwise indicating a firing command) the control system will arrest the firing of the firing mechanism of the firearm. Examples of such firing requests are set forth, and monitored, as indicated in step 1013. Thus, as indicated in subsequent step 1015, if such a movement and/or acceleration exceeding such thresholds is sensed and communicated to the control system during the currently set time period, the control system proceeds to step 1017, in which it so prevents the firing of the firing mechanism (and shooting of the firearm). If, by contrast, the movement of the firearm and/or device is below the threshold(s) during the time period, the control system may proceed to step 1019, in which it causes the firearm to shoot (e.g., actuating the firing mechanism and/or ending the operation of a safety). The control system may then return to the starting position.

In some embodiments, where a decreasing movement and/or acceleration, and/or a movement increasing the alignment of the firearm with a point of impact is determined to be taking place, the control system may implement a delay before firing the firearm (or, releasing the firing arrest) increasing the accuracy of the shooting the firearm. In some embodiments, such a period of the delay may be selected to coincide with an optimal time of alignment of the firearm with the point of impact selected. Some example methods for setting and selecting points of impact are set forth in greater detail, above. Similarly, in some embodiments, the control system may arrest or actuate the firearm based on other factors and conditions, and whether the state of those other factors and conditions are optimal, or within thresholds or amounts, set by the user and/or control systems. For example, in some embodiments, any of the ballistic and other accuracy-impacting factors discussed above in this application may be sensed by computer hardware, and thresholds and amounts may be set with the aid of custom

software running thereon, implementing steps similar to those set forth in reference to FIG. 10, with respect to those other factors.

Any of the steps set forth above, and in this application, are only examples, and are not exhaustive or exclusive expressions of the many, and virtually unlimited, alternative steps, orders of steps, numbers of steps, and overall methods that may be carried out, within the scope of the invention. Any of the embodiments of devices, systems, methods, steps, and techniques set forth above may be combined with any other embodiments of devices, systems, methods, steps, and techniques so set forth, in additional embodiments of the invention. Such alternative embodiments will be apparent to those of ordinary skill in the art.

I claim:

1. A device for aiding a user(s) in aiming a firearm, comprising:

a sensor(s);

a control system including specialized computer hardware and software performing calculations related to ballistics of a projectile aimed at a target or a target-surrounding environment;

a display overlaying point of impact indicator(s), indicating a predicted or actual point(s) of impact of a projectile(s), within a view of said target and said target-surrounding environment, based on said calculations related to ballistics of said projectile aimed at said target or said target-surrounding environment;

communications hardware, adapted for carrying communications between said display and said control system; and

a housing.

2. The device for aiding a user(s) in aiming a firearm of claim 1, wherein the display comprises augmented reality display hardware.

3. The device for aiding a user(s) in aiming a firearm of claim 2, wherein said display is at least partially transparent, transmitting environmental light from said target-surrounding environment and creating an at least partially artificial image including virtual object(s).

4. The device for aiding a user(s) in aiming a firearm of claim 3, wherein said virtual object(s) comprise said point of impact indicator(s).

5. The device for aiding a user(s) in aiming a firearm of claim 1, comprising a camera, wherein said camera is or comprises at least one of said sensor(s).

6. The device for aiding a user(s) in aiming a firearm of claim 1, wherein said display comprises an electronic viewfinder collocated with a telescopic sight comprised in said device.

7. The device for aiding a user(s) in aiming a firearm of claim 6 wherein said electronic viewfinder is located on or over said telescopic sight.

8. The device for aiding a user(s) in aiming a firearm of claim 6 wherein said electronic viewfinder is adapted to be placed onto said telescopic sight.

9. The device for aiding a user(s) in aiming a firearm of claim 6 wherein said electronic viewfinder is adapted to overlay virtual objects within said view of said target and said target-surrounding environment.

10. The device for aiding a user(s) in aiming a firearm of claim 6 wherein said electronic viewfinder is mounted on said firearm.

11. The device for aiding a user(s) in aiming a firearm of claim 1 wherein said communications hardware includes wired communications hardware.

12. The device for aiding a user(s) in aiming a firearm of claim 1 wherein said communications hardware includes wireless communications hardware.

13. The device for aiding a user(s) in aiming a firearm of claim 1, wherein said point of impact indicator(s) indicate(s) a predicted point of impact of said projectile.

14. The device for aiding a user(s) in aiming a firearm of claim 1, wherein said point of impact indicator(s) indicate(s) an actual point of impact of said projectile, after said projectile has been sent to said target or target-surrounding environment.

15. The device for aiding a user(s) in aiming a firearm of claim 1, wherein an aspect of the point of impact indicators indicates whether a projectile, if sent by said firearm, is predicted to cause 1) an injury lethal to the target or 2) an injury disabling the target or 3) a non-lethal, non-disabling strike within the target-surrounding environment.

16. The device for aiding a user(s) in aiming a firearm of claim 1, wherein the control system comprises and/or is communicatively connected with a smart bullet, comprising:

at least one sensor, configured to determine a position, motion and/or orientation of said smart bullet while said smart bullet is in-flight;

at least one actuator(s) configured to steer said smart bullet in response to communications while said smart bullet is in-flight;

a local control system, on board said smart bullet, comprising specialized computer hardware and software, configured to receive communications, with a computer system positioned in a remote location from said smart bullet based on calculations related to ballistics of said smart bullet;

at least one antenna configured to receive said communications with a computer system positioned in a remote location from said smart bullet, being so communicatively connected with said local control system; and

an at least partially streamlined housing, generally in the form of a bullet.

17. The device for aiding a user(s) in aiming a firearm of claim 16, wherein the smart bullet comprises at least one moving sub-component.

18. The device for aiding a user(s) in aiming a firearm of claim 17, wherein the smart bullet comprises a dampener protecting said at least one moving sub-component during impact of said smart bullet with a target.

19. The device for aiding a user(s) in aiming a firearm of claim 16, wherein said communications with a computer system positioned in a remote location from said smart bullet are based on a pre-planned flight path to a target within a target-surrounding environment.

20. The device for aiding a user(s) in aiming a firearm of claim 16, wherein the smart bullet is configured to penetrate a target, sense condition(s) and/or a location within said target, and communicate information related to said conditions and/or location wirelessly to a computer system in a remote location from said smart bullet.
